GYROSCOPIC STEERING MECHANISM

SEARCHED AND FILED COPY

1,318,980:

Specification of Letters Patent.

Patented Oct. 11, 1919

Application filed August 27, 1918. Serial No. 251,641.

To all whom it may concern:

Be it known that I, WILLIAM DIETER, a citizen of the United States of America, residing in the borough of Brooklyn, county 5 of Kings, city and State of New York, have invented certain new and useful Improvements in Gyroscopic Steering Mechanisms, of which the following is a specification.

This invention relates to gyroscopic steering mechanisms, such as are used for steering automobile torpedoes. In such mechanisms, the gyroscope is spun up either by a spring motor or by the action of compressed air upon a turbine, this spinning-up occurring 10 ring while the torpedo is still within the launching tube, or before it loses the direction or aim given it by such tube. It is desirable to provide means for keeping the gyroscope spinning at a sufficiently high speed 15 during its run, and for this purpose the use of compressed air at reduced pressure has been proposed.

According to the present invention, the gyroscope is spun up by air at high pressure, 20 being preferably the full initial pressure in the air flask, and is maintained spinning by the turbine effect of jets of air at reduced pressure taken from the exhaust of one or both the servo-motors of the torpedo, the 25 intermittent exhaust being stored up and equalized in a supplemental reservoir or bottle, so that a substantially steady flow of air at diminished pressure is led to the gyroscope or fly wheel and caused to impinge 30 thereon for keeping it up to speed.

The preferable embodiment of the invention is shown in the accompanying drawings wherein:—

Figure 1 is a schematic view, being in part 40 a fragmentary vertical section through the torpedo, illustrating in elevation so much of the internal mechanism as pertains to this invention;

Fig. 2 is a sectional elevation on a larger 45 scale of the gyroscope and its spinning mechanism;

Fig. 3 is a section of the upper part of the exhaust equalizing reservoir or flask.

Referring to Fig. 1, in which the parts 50 are rearranged in diagrammatic fashion, so as to illustrate their relations, A designates the shell or hull of a portion of the torpedo, B is the compressed air pipe leading from the air reservoir or flask, C is the pressure

reducing valve, D is the superheater, E is the casing containing the gyroscope, F is the servo motor controlled by the gyroscope in any usual manner (the controlling means not being shown), and G is the rudder for horizontal steering operated from said motor. H is the servo-motor of the depth or immersion mechanism and I is the horizontal rudder for steering to depth, being operated from the servo-motor H in the usual manner. All of the parts thus described 65 may be of any known or usual construction and arrangement.

Referring to Fig. 2, the gyroscope J is shown partly in dotted lines and partly by breaking away the casing E. The gyroscope is of any usual construction, comprising a fly wheel a pivoted within a normally horizontal gimbal ring b, which in turn is pivoted within a vertical gimbal ring c, which is pivoted on a vertical axis to a supporting portion d of the casing E. The respective pivots are commonly ball bearings, as is shown at the bottom pivot, which is shown in section. Before spinning, the gyroscope is held locked in an invariable 80 position, as by means of a locking bolt e entering a recess f in the ring b axially with the fly wheel. The gyroscope is spun by a turbine g rotated by jets of compressed air from a nozzle h, this air being led from the 85 high-pressure side of the pressure regulator C, through the pipe i. Consequently, the gyroscope is spun up by air of the initial high pressure in the air flask, which usually exceeds 2200 pounds per square inch. The 90 turbine g is mounted as usual on a shaft which communicates rotation to the fly wheel through pinions j k, in the usual manner, and at the end of the spinning operation, the turbine is displaced to throw these 95 pinions out of mesh and at the same time the bolt e is withdrawn to unlock the gyroscope. The described construction of gyroscope is that commonly used in the Bliss-Leavitt torpedoes and is fully set forth in 100 the patent to Leavitt, No. 1,185,210, dated May 30, 1916.

Air for driving the servo-motors F and H is taken as usual from the low-pressure side of the pressure-reducing valve C, 105 through the pipe m which is shown as leading to the inlet n of H and thence to the inlet p of F. Heretofore the exhaust from

these two motors has been into the air chamber within the hull A, the exhaust openings located at q and r, respectively, having been open.

- 5 According to the present invention, a pipe or tube s has branches connected to the respective branch openings q r r, and conducts the exhaust therefrom into an equalizing reservoir t, from which it is led by 10 a tube u to the gyroscope, the air being conducted to a jet nozzle v, by which the air jets are directed obliquely or tangentially against the fly wheel a, impinging upon notches or buckets formed peripherally 15 therein so that they serve to urge the wheel forward and keep it up to its normal speed.

The pressure on the outlet side of the reducer C may vary, according to the speed at which the propelling engine or turbine of 20 the torpedo (not shown) is to be driven, but it usually varies between 400 and 600 pounds per square inch. This pressure is conducted through the pipe m to the servo-motors, and is made effective to operate, 25 more or less intermittently, the pistons or plungers of these motors, which in turn operate the rudders. The servo-motors operate with such excess of power that it is quite feasible to subject their exhaust to a 30 certain amount of back pressure, as for example, in the neighborhood of 50 pounds per square inch.

Theoretically, the exhaust might be conducted from these servo-motors directly to 35 the tube u, and thence to the jet for maintaining the gyroscope in rotation; but, as the exhaust is intermittent, this would not give the desired continuous flow of air to the fly wheel. By conducting the exhaust 40 into the small reservoir t, the impulses are stored up and an approximately uniform pressure is maintained with consequently a constant flow at approximately uniform pressure to the maintenance turbine jet. To 45 avoid excessive back pressure upon the servo-motors, such as might deprive them of adequate power, or even stall them, I provide a relief valve w for discharging excess pressure from the reservoir t. The 50 construction of this relief valve may be varied, but that shown in Fig. 3 is suitable, the valve being pressed down by a spring x which reacts against the screw-plunger y, which may be adjusted to vary the pressure 55 and may be set by the nut z. Thus, whenever the pressure exceeds that for which the relief valve is set, the exhaust pressure

flows out through this valve and escapes around its stem or a special orifice outlet a'.

The special construction of the maintenance turbine may be varied. The construction shown in Fig. 2 involves formation of the fly wheel a with notches, or preferably deep buckets b', against which the air blows from one or more jet orifices v, these orifices 65 being inclined as usual, so as to direct the air jets tangentially. The air from the tube u is directed into a central chamber within the plug e' and flows up thence through a central perforation in a disk d', 70 and thence through a central tube e' within the ball bearing, the air being thence delivered into the chamber in the ring c supplying the jet orifices. The pressure of the delivered air may be varied by replacing 75 the disk d' with one having a larger or smaller perforation.

This construction of maintenance turbine is set forth in my pending application No. 219,202, filed February 26, 1918. 80

It is not necessary that the exhaust air be taken from both the servo-motors, as it may be taken from either. If only one be used, it is preferable to take it from the motor F, from which exhaust impulses are 85 emitted with sufficient frequency and regularity for the purpose.

The construction with respect to details and arrangement may be varied without departing from the invention which is set forth 90 in the following claims.

I claim as my invention:—

1. In a torpedo, in combination with a source of compressed air, a reducing valve, a gyroscope, spinning means therefor, and a servo-motor fed with air from the reduced-pressure side of said valve, of air-impelled means for maintaining the gyroscope in rotation, and means for conducting thereto exhaust air from said motor. 100

2. The means of claim 1, combined with a reservoir receiving the exhaust from said motor and delivering air to said maintaining means.

3. The means of claim 2, with a relief valve for discharging excess pressure from said reservoir. 105

4. The means of claim 1, combined with adjusting means for reducing the pressure of the air fed to said maintaining means. 110

In witness whereof, I have hereunto signed my name.

WILLIAM DIETER.
